UNITED STATES PATENT OFFICE.

WILHELM HENNING PETERSÉN, OF GAMLA POSTEN, LUDVIKA, SWEDEN, ASSIGNOR TO
ALLMANNA SVENSKA ELEKTRISKA AKTIEBOLAGET, OF VÄSTERÅS, SWEDEN, A
CORPORATION OF SWEDEN.

TIME RELAY.

Application filed November 4, 1924, Serial No. 747,852, and in Sweden December 10, 1923.

Time relays based on the thermic principle, that is, in which the heat produced in a resistance member by the traversing current is stored up in a body and after increasing the temperature of said body up to a certain limit, in some way causes a movement leading to release, are often considered as appropriate especially for the protection of small load objects, as separate motors or heating elements. This is for the reason, that such relays are adapted for copying, more or less truly, the temperature fluctuations of the load object, and can thus be readily adjusted to release even at the instant when there is real danger. The release is generally effected either by the fusion of the resistance member or of an adjacent part, which is rather unsuitable, as it necessitates the insertion of spare parts, or by deformations caused by the heat, which however are comparatively small and slow and therefore must be combined with a special mechanism with springs or electromagnets for the releasing movement. In this way a comparatively complicated system of movable parts is obtained which may easily get in disorder.

The present invention relates to a time relay comprising a heating member and an electromagnet, but having a minimum of movable parts and therefore being extremely simple and reliable. The characteristic feature of the invention is that the heating member itself or a part in close connection therewith forms part of the magnetic circuit and consists of a material which is ferromagnetic at ordinary temperature but becomes only feebly magnetic at a comparatively low rise of temperature, so that it will act as a large air-gap in the magnetic circuit and reduce the attraction on an armature sufficiently to permit it to be pulled away from the magnet and effect release. The rest of the magnetic circuit preferably is composed mainly of iron, and the heating member forming part thereof may lie immediately adjacent to the air-gap between the fixed portion of the circuit and the armature, which is generally to be preferred, or in other place.

Iron and alloys with a comparatively great percentage of iron generally do not lose their ferromagnetic properties until a rather high temperature (red heat) is

reached, and are therefore generally less suitable for the present purpose, although cases may be imagined where they can also be employed. Nickel, on the contrary, is particularly suited, alone as well as in certain alloys. Pure nickel loses entirely its ferromagnetic properties at about 300° C., and its natural alloy with copper, so-called Monel metal (containing about $\frac{2}{3}$ Ni and $\frac{1}{3}$ Cu) already at about 90°-100° C. By alloying nickel with copper in other proportions, nearly any value of the critical temperature below 300° may be obtained. In some cases the relation between the permeability and the temperature follows rather a straight line, in others the former sinks more rapidly at a certain critical value of the latter. Both forms may be employed, but the last-mentioned one is generally more suitable.

Another type of alloys which have ferromagnetic properties at ordinary temperature but lose these at a comparatively low rise of temperature, are the so-called Heusler alloys, consisting of aluminium and manganese with or without an addition of copper.

A preferred form of the invention is shown in the accompanying drawing in a side view in Fig. 1 and in a plan view (with certain parts taken away) in Fig. 2.

1 is an electromagnet having a three-legged core, in the middle leg of which the armature 2 is rotatably mounted so as to occupy different positions, depending upon whether the attraction from one outer leg or the other is the stronger one. Normally the armature is assumed to be more strongly attracted by the left leg so as to be kept in the position shown in the drawing. Between the iron core proper of this leg and the armature there is, however, inserted a piece 3 of a nickel-copper alloy or the like which is heated by the influence of the current. In the form shown this is effected thereby, that the piece 3 which is slotted in zig-zag, is traversed by the secondary current from a current transformer, the core of which is formed by the electromagnet 1, and the primary winding by the coil 4 of the latter. The secondary winding is a coil 5 on the same core, having few turns.

When the current in the coil 4, thus also in the resistance member 3, is increased

above a certain value, the temperature in said member rises so much that its permeability sinks substantially below its normal value. The magnetic induction is therefore forced over in the other leg of the magnet, and finally the attraction thereof will predominate, so that the armature is thrown over and operates a movable contact 6 which it presses against a stationary 10 pole 7, or performs any other suitable releasing movement. The arrangement may be such, that the releasing motion does not take place until the member 3 has practically lost its ferromagnetic properties, or 15 such that release occurs already when its permeability has been substantially reduced.

The adjustment of the relay for different intensities of current or for different releasing time limits can be effected in a known 20 manner, in part by connecting a greater or smaller portion of the primary magnet coil 4 in circuit by means of a series of taps 8 in

part by a screw 9 regulating the normal value of the air gaps at the two ends of the armature. A spring 10 keeps the armature 25 in its normal position when there is no current on the relay.

Having thus described my invention and the manner of its operation, I declare that what I claim is:—

In electric relays, a three-legged iron core, a winding on the middle leg thereof, an armature pivoted in said middle leg, means for holding said armature normally in such position as to make the attractive 30 force of one outer leg stronger than that of the other, a body losing its permeability at low temperature in the first of said outer legs, and means for electrically heating said body to sufficient temperature to reduce substantially its permeability.

In testimony whereof I have signed my name to this specification.

WILHELM HENNING PETERSÉN
